ARTHUR E. PEW, JR., OF BRYN MAWR, AND HENRY THOMAS, OF RIDLEY PARK, PENNSYLVANIA, ASSIGNEES TO SUN OIL COMPANY, OF PHILADELPHIA, PENNSYLVANIA, A CORPORATION OF NEW JERSEY.

PROCESS OF DISTILLING MINERAL OIL.

Application filed May 29, 1926. Serial No. 112,443.

In applications filed by us March 5, 1925, Serial No. 13,040 and March 13, 1925, Serial No. 15,262, we have disclosed a practical and commercially operative process and apparatus for fractionally distilling mineral oil by heat exchange between mercury vapor and the oil to be distilled, the oil being partly vaporized and the mercury vapor being condensed and returned to a body of liquid mercury which is continuously generating mercury vapor. In this process a stream of oil flows through a series of confined spaces, preferably in the form of a rapidly flowing solid stream of approximately uniform thickness and width and of very small depth relatively to its width and of small width relatively to its length. The mercury vapor generated in the mercury boiler is at such pressure that it will have a temperature of condensation above that of the hottest part of the stream of oil, which is the oil flowing through the last space of the series. The mercury vapor flows into confined paths, or chambers, arranged in multiple with respect to each other and in heat exchange relation with the respective confined spaces, or oil vaporizing conduits, through which the oil is flowing in series. The amount of mercury vapor admitted to each chamber is sufficient to effect, by heat exchange and condensation of the mercury vapor, partial vaporization of the oil flowing through each of said confined spaces. The proportion of oil vaporized in each vaporizer is predetermined by independently regulating the rate of flow of the mercury vapor into the mercury chamber of each vaporizing unit. This may be done by means of valves located at or near the admission openings into the several mercury chambers.

In such process, however, the pressure of mercury vapor and the temperature at which it condenses may be the same in the mercury vapor chambers of all the vaporizer units. This does not militate against the successful operation of the process, particularly because, compared with other heating media, the difference in temperature between the mercury vapor and the hottest part of the oil stream need be relatively low, and hence, even in the last vaporizing unit of the series, the temperature of the mercury vapor need not be so high as to effect cracking (decompo-

sition) of the oil; which, in ordinary distillation processes, even where the oil is under vacuum, is a serious cause of damage to the distillate. Hence, it is practicable to feed to all the vaporizing units mercury vapor at the same pressure and temperature, which must of course be high enough to effect vaporization of the higher boiling point fractions in the last vaporizer of the series.

It is, however, desirable, from the standpoint of economical operation, to maintain a minimum practicable temperature difference between the mercury and the oil in the several vaporizing units. This is accomplished, to a degree, in the process and apparatus of our said application, wherein two mercury boilers are provided, which generate mercury vapor at different temperatures, and in which the vaporizing units are divided into two sets or series, the first of which utilizes mercury vapor from one boiler at a relatively low pressure and temperature and the second of which utilizes mercury vapor from the other boiler at a relatively high pressure and temperature.

It is however, desirable to avoid the use of a plurality of boilers, and it is also desirable to secure a minimum practicable temperature difference between the mercury and the oil in each vaporizer unit. In the present invention, this object is accomplished. Only one mercury boiler, operating under a constant pressure, is required, while means are afforded whereby any desired pressure and temperature of condensation, not exceeding that in the boiler itself, may be established in the mercury vapor chamber of any vaporizer unit.

It will also be understood that with a low pressure in the mercury vapor chamber and in the condensate return pipes leading therefrom, the boiler pressure is effective to back up the liquid mercury in the condensate return pipes, thus necessitating the positioning of the vaporizing units at a relatively high altitude, which involves additional expense of construction and inconvenience of operation. A further object of our invention is to avoid the necessity of positioning the vaporizers at an inconveniently high level, which object is accomplished in the present invention.

In the drawings, which show a preferred

construction in which our new process is adapted to be practiced with superior efficiency:

Fig. 1 is a diagrammatic view of a part of an oil distilling plant in which our new process is adapted to be practiced.

Fig. 2 is a diagrammatic view of a larger part of the same plant.

Referring first to Fig. 1:

One end of one of the vaporizing units *a* comprising a chamber *b* for the oil and, in heat exchange relation therewith, a chamber *c* for the reception of mercury vapor, is shown in the upper left-hand corner of Fig. 1. This vaporizing unit is an elongated cylinder divided into said chambers by means of a longitudinally extending pan or partition, slightly inclined to the horizontal, and down along which the oil is adapted to flow at considerable speed and spread out thereon into a thin wide stream. The mercury boiler *d*, which is shown only in diagram, communicates with mercury vapor feed pipe *e*, which in turn communicates with the mercury vapor chamber *c* of the vaporizer unit. A valve *f* controls the flow of mercury vapor into chamber *c*.

A mercury vapor condensate outlet pipe *g* may connect directly with, or constitute the upper end of, a pipe section *j* hereinafter described, but it is preferred to connect the pipe directly with the upper end of a cup *h*, which, together with the goose-neck pipe *i*, constitutes a liquid mercury seal, or trap. Any sediment will collect in this trap, which may be cleaned at intervals, if necessary. The pipe *g* and the vapor space at the top of the cup *h*, connects, by means of a pipe *n*, with the upper end of the inflow section *j* of a pipe *m*, which section extends downward for a considerable distance, thence upward for a distance equal to half the length of its downward extension (forming a U-shaped section *k*) and thence laterally, in a slightly downwardly inclined direction either direct to the vapor space of the boiler, or preferably, as shown, to a vapor space at the top of a vessel *o*, which extends below the level of the liquid mercury in the boiler and connects therewith by means of a liquid mercury pipe *p*. The vapor space in vessel *o* should communicate with the vapor space on the boiler, as, for example, by means of a pipe *u* connecting pipe *m* and the mercury vapor feed pipe *e*.

The desirable depth of the U-shaped pipe section *k* below the lateral outflow section of pipe *m* and the desirable height of the pipe section *j* above the lateral section of pipe *m* will depend on the pressure which it is intended to maintain in the boiler. If the boiler pressure be assumed to be 30 pounds absolute, the height of pipe section *j* and the depth of pipe section *k* should be 60 inches.

If it be assumed that the pressure in cham-

ber *c* of the vaporizer unit be the same as the boiler pressure, it is clear that the two columns of liquid in the U-shaped pipe section *k* will have a common level, as shown on the drawings. Assume, however, that a reduced pressure is established in the chamber *c* of the vaporizer unit. In this case, the liquid mercury would be forced down the right-hand limb of pipe section *k* and up the left-hand limb thereof and into pipe section *j* until an equilibrium of pressures is established. If it be assumed that an absolute vacuum is established in the mercury vapor chamber *c*, the liquid mercury vapor would be forced half way to the bottom of the right-hand limb of pipe section *k* and would rise half way to the top of pipe section *j*; that is, the level of the left-hand column would be 60 inches above the level of the right-hand column. In either assumed case, as mercury condensate runs into pipe *j*, the levels of both columns would rise in unison until the right-hand limb of pipe section *k* is filled, after which the condensate would continuously overflow into the laterally extending section of pipe *m*. This condition would exist in normal operation.

Throttling valve *f* so as to constrict the flow of mercury vapor thereinto tends to reduce the pressure and therefore the temperature of condensation of the mercury vapor in chamber *c*. The arrangement shown permits and compels such a result. It is, therefore, apparent that by a mere manipulation of valve *f*, not only may the rate of flow of mercury vapor into the corresponding chamber *c* be regulated, but any desired absolute pressure may be established in such chamber. It, therefore, becomes possible to reduce to any desired minimum the temperature difference between the mercury in chamber *c* and the oil in chamber *b*. It becomes possible, also, to progressively increase the temperature in the mercury chambers of successive vaporizing units, so that, as the oil is gradually raised in temperature, the temperature difference between the mercury and the oil in all the vaporizing units may be maintained as nearly uniform as may be desirable.

In practice, the absolute pressures in the mercury vapor chambers of all the vaporizing units, or in all except the last unit of the series, will be less than boiler pressure, so that there will be a column of mercury condensate in pipe section *j*.

As the mercury condenses and flows into the cup *h*, it flows out of pipe *i* into pipe section *j* and a corresponding amount of condensate flows out of pipe section *k* into the laterally extending part of pipe *m*, whence it flows into vessel *o*.

It is desirable to maintain a constant boiler pressure, which it would be difficult, if not practically impossible to do, without some special provisions. That is, it is necessary

to generate mercury vapor at a rate not less than the rate at which it is admitted to the vaporizer units, and to insure this it is practically necessary to generate mercury vapor 5 at a rate slightly exceeding the rate at which it is admitted to the vaporizer units. Without some special provision to prevent it, this would result in a gradual building up of the mercury vapor pressure in the boiler and the 10 feed line. Such special provision is disclosed in our said first application, but it is preferred to utilize the means herein shown and which will now be described.

A pipe *r* from the mercury vapor feed or 15 supply line *e* communicates with a container *s* which contains a small chamber *t* having a small mercury vapor inlet in which seats a pressure control valve *v*, the stem of which is loaded by a weight *w*. The weight of the 20 valve is such that it will open when the pressure of mercury vapor exceeds the desired mercury boiler pressure. Chamber *t* communicates with a condenser *x* and beyond it with a pipe *y* having at its lower end a goose-neck *z*. 25 Assuming a boiler pressure of thirty pounds absolute, the goose-neck *z* should be 60 inches in height, and the pipe *y* should extend 60 inches above the goose-neck. The latter may connect direct with the vapor space of the 30 mercury boiler or with the vapor space of the vessel *a* or with any vessel or pipe similarly connected with the boiler.

Any mercury vapor that enters chamber *t*, due to rise in boiler pressure above 30 35 pounds, will be condensed in condenser *x* and will flow down pipe *y* while a corresponding amount of condensate will flow into vessel *o*.

Fig. 2 shows in diagram the principal elements of a complete plant. In addition to vaporizer *a*, any number of additional vaporizers 10 and 11 are provided, the mercury chambers of which are respectively connected with branch inlet pipes 12 and 13 respectively controlled by valves 14 and 15. The mercury vapor chambers of vaporizers 10 and 11 are also provided with the mercury condensate outlet pipes 16 and 17, all of the condensate pipes being connected with the mercury boiler by means similar to those connecting mercury condensate pipe *y* with the mercury boiler.

The oil from a source of supply flows into and through the oil vaporizer space of vaporizing unit 10 at a rapid rate, spreading out over the partition separating this space from the mercury chamber in a thin sheet so as to bring every particle of the oil in heat exchange relation with the mercury vapor 55 and condensing a fraction thereof whose percentage relative to the entire volume of oil admitted will depend (principally) on the length of time to which the oil is exposed to the heat and to the temperature of the mercury vapor. The temperature of the mercury

vapor is regulated by regulating its pressure, which is regulated by throttling the valve 14 (corresponding to valve *f* of Fig. 1) as heretofore explained. The oil vapors pass directly out the top of the oil vaporizing space 70 to a condenser (not shown). The residue which constitutes the dominant proportion of the oil admitted, then flows through pipe 20 to the next vaporizing unit 11, wherein a similar operation occurs, a higher boiling point 75 fraction being vaporized. In this vaporizing unit, the temperature of the mercury vapor is preferably higher than in vaporizing unit 10, which higher temperature is obtained by throttling the valve 15 to a less degree than valve 14 is throttled. In the last vaporizing unit *a* of the series into which the residue from all the other vaporizers is admitted through pipe 21, the valve *f* need not be throttled at all, so as to allow the mercury vapor 85 therein to be, if desired, at boiler pressure.

While mercury is preferred as the direct heating medium, it is possible to substitute other vaporizable metals, such as cadmium and zinc.

Provision should be made for evacuating the mercury vapor system at the beginning of a run in order that no air may be present in the system at the start. For this purpose there is shown a valved pipe *e'* communicating with the vapor feed pipe *e* and adapted to be connected with a vacuum pump (not shown).

While the invention finds its probably most useful application in the distillation of lubricating oil from topped crude oil, it is adapted, also, to the distillation of crude oil which has been cracked and afterward purified by chemical treatment. The invention is also applicable to the distillation of higher constituents from the crude oil itself or from crude oil from which has been distilled off only part of such lighter constituents. To adapt the invention to any kind of distillation, it is necessary only to suitably modify 105 the pressure and temperature factors, which modification is within the capacity of those skilled in the art of refining oil.

We do not herein claim the apparatus herein described, as this forms the subject-matter of a separate application.

Having now fully described our invention, what we claim and desire to protect by Letters Patent is:—

1. The process of distilling mineral oil 120 which comprises flowing a stream of oil continuously into, through and out of a confined space, generating mercury vapor from a body of liquid mercury, flowing mercury vapor toward and into a confined path in 125 heat exchange relation with the oil in said space and partly vaporizing the oil and condensing the mercury vapor, maintaining in said confined path a vapor pressure substantially less than the autogenous pressure on 130

the body of liquid mercury, returning the mercury condensate to said body of liquid mercury and in the return of liquid condensate flowing the condensate through a vapor space subject to the vapor pressure in said confined path and downward and upward through balancing columns of liquid mercury whose heights differ in accordance with the different pressures to which they are exposed.

2. The process of distilling mineral oil which comprises flowing a stream of oil continuously into, through and out of a confined space, generating mercury vapor from a body of liquid mercury, flowing mercury vapor toward and into a confined path in heat exchange relation with the oil in said space and partly vaporizing the oil and condensing the mercury vapor, maintaining in said confined path a vapor pressure substantially less than the autogenous pressure on the body of liquid mercury, returning the mercury condensate to said body of liquid mercury and in the return of liquid condensate flowing the condensate through a vapor space subject to the reduced pressure in said confined path and successively downward and upward through balancing columns of mercury whose relative heights vary with the variation in the extent to which the pressure in said confined path is reduced below that on the said body of liquid mercury.

3. The process of distilling mineral oil which comprises flowing a stream of oil continuously into, through and out of a confined space, generating mercury vapor from a body of liquid mercury, flowing mercury vapor toward and into a confined path in heat exchange relation with the oil in said space and partly vaporizing the oil and condensing the mercury vapor, maintaining in said confined path a vapor pressure substantially less than the autogenous pressure on the body of liquid mercury, returning the mercury condensate to said body of liquid mercury and in the return of liquid condensate flowing the condensate through a vapor space communicating with the vapor space in said confined path and through a column of said condensate whose hydrostatic pressure is sufficient to balance the difference in vapor pressures on the body of liquid mercury and in said confined path.

4. The process of distilling mineral oil which comprises flowing a stream of oil continuously into, through and out of a confined space, generating mercury vapor from a body of liquid mercury, flowing mercury vapor toward and into a confined path in heat exchange relation with the oil in said space and partly vaporizing the oil and condensing the mercury vapor, maintaining in said confined path a vapor pressure substantially less than the autogenous pressure on the body of liquid mercury, returning the mercury condensate

to said body of liquid mercury and in the return of liquid condensate flowing the condensate through a vapor space communicating with the vapor space in said confined path and a vapor space in communication with the mercury vapor flowing from said body of mercury and establishing between said vapor spaces a column of said condensate whose hydrostatic pressure is sufficient to balance the difference between the vapor pressure in said vapor spaces.

5. The process of distilling mineral oil which comprises flowing a stream of oil continuously into, through and out of a confined space, generating mercury vapor from a body of liquid mercury, flowing mercury vapor toward and into a confined path in heat exchange relation with the oil in said space and partly vaporizing the oil and condensing the mercury vapor, maintaining in said confined path a vapor pressure substantially less than the autogenous pressure on the body of liquid mercury, retaining the mercury condensate to said body of liquid mercury and in the return of liquid condensate flowing the condensate through a vapor space subject to the vapor pressure in said confined path and downward and upward through balancing columns of liquid mercury, and thence through a vapor space in communication with the mercury vapor flowing from said body of mercury toward said confined path.

6. The process of distilling mineral oil which comprises flowing a stream of oil continuously into, through and out of a confined space, generating mercury vapor from a body of liquid mercury, flowing mercury vapor toward and into a confined path in heat exchange relation with the oil in said space and partly vaporizing the oil and condensing the mercury vapor, maintaining in said confined path a vapor pressure substantially less than the autogenous pressure on the body of liquid mercury, returning the mercury condensate to said body of liquid mercury and in the return of liquid condensate flowing the condensate through a vapor space into a second body of liquid mercury condensate in which sediment is adapted to be trapped, and thence through balancing columns of liquid mercury whose heights differ in accordance with the different pressures to which they are exposed.

7. The process of distilling mineral oil which comprises flowing a stream of oil continuously into, through and out of a confined space, generating mercury vapor from a body of liquid mercury, flowing mercury vapor toward and into a confined path in heat exchange relation with the oil in said space and partly vaporizing the oil and condensing the mercury vapor, maintaining in said confined path a vapor pressure substantially less than the autogenous pressure on the body of liquid mercury, returning the mercury condensate

- sate to said body of liquid mercury and in the return of liquid condensate flowing the condensate through a vapor space subject to the vapor pressure in said confined path and downward and upward through balancing columns of liquid mercury, and thence into a second body of liquid mercury communicating with the first body of liquid mercury and having a vapor space in communication with the mercury vapor flowing from said body of mercury toward said confined path.
8. The process of distilling mineral oil which comprises flowing a stream of oil continuously into, through and out of a confined space, generating mercury vapor from a body of liquid mercury, flowing mercury vapor toward and into a confined path in heat exchange relation with the oil in said space and partly vaporizing the oil and condensing the mercury vapor, maintaining in said confined path a vapor pressure substantially less than the autogenous pressure on the body of liquid mercury, returning the mercury condensate to said body of liquid mercury and in the return of liquid condensate flowing the condensate through a vapor space into a second body of liquid mercury in which sediment is adapted to be trapped, and thence through balancing columns of liquid mercury, and thence, through a vapor space in communication with the mercury vapor flowing toward said confined path, into a third body of liquid mercury in communication with the first body of liquid mercury.
9. The process of distilling mineral oil which comprises continuously flowing a stream of oil successively through a series of confined spaces, subjecting a body of liquid mercury to heat and driving out mercury vapor at a temperature substantially above that of the oil flowing through the last space of the series, flowing such mercury vapor into a plurality of confined paths in heat exchange relation with the respective confined spaces to effect, by heat exchange and condensation of mercury vapor, partial vaporization of the oil flowing through each of said confined spaces, and returning the mercury condensed in each of said confined paths to said body of liquid mercury, maintaining differential pressures in a plurality of said confined paths by differentially regulating the rate of flow thereinto of mercury vapor, and in the return of said condensate from each of said confined paths flowing it through a vapor space subject to the pressure in said confined path and downward and upward through balancing columns of mercury whose relative heights automatically vary with the variations in the extent to which the pressure in such confined path is reduced below that on said body of liquid mercury.

In testimony of which invention, we have hereunto set our hands, at Marcus Hook, Pennsylvania, on this 18th day of May, 1926.

ARTHUR E. PEW, JR.
HENRY THOMAS.
